UNITED STATES PATENT OFFICE.

JOSEPH FREDERICK NORMAN, OF LONDON, ENGLAND, ASSIGNOR OF ONE-HALF TO
NORMAN TYPE CASTING SYNDICATE LIMITED, OF LONDON, ENGLAND.

TYPE-CASTING MACHINE.

1,165,997.

Specification of Letters Patent.

Patented Dec. 28, 1915.

Application filed June 6, 1912. Serial No. 702,035.

To all whom it may concern:

Be it known that I, JOSEPH FREDERICK NORMAN, a subject of the King of England, residing at London, in the Kingdom of England, have invented a new and useful Type-Casting Machine, of which the following is a specification.

This invention relates to that kind of type casting machine in which a plurality of 10 matrices and molds are carried on a sliding carrier and successively brought before the orifice of a pot containing molten type metal so that each type is cast separately and after being nicked and trimmed is ejected from 15 the molds.

It is my object to provide a simple and reliable machine of this kind which is double acting and will perform the work in an expeditious manner, and I obtain this object 20 by adopting a straight bed fitted with an endwise reciprocating carrier furnished with transversely sliding matrices between fixed molds connected with said carrier and traveling over a stationary mold plate, said matrices being controlled by cams situated at 25 each side of the headstock for ejecting the finished type one after another.

The invention is illustrated in the accompanying drawings, in which:—

30 Figure 1, is a front elevation of the left half of the machine, the right half being identical to the former; Fig. 2, is a corresponding plan; Fig. 2^a is a portion of said plan drawn to a larger scale and with the top parts removed; Fig. 3, is an end elevation of same to a larger scale but with the matrices omitted; Fig. 4, is a cross-section at the middle of the machine; Fig. 5, is a cross-section taken at the point of ejection 35 of the type; Figs. 6 and 7, are a plan and a side elevation respectively, to a larger scale, of a fixed side of the mold; Figs. 8 and 9, are a side elevation and plan respectively of a matrix having adjustable heel-studs and 40 Fig. 10 is a partial plan view of the machine. Fig. 11 is a perspective view partly in section of the various mold parts, showing both the mold sides and matrices, and Fig. 12 is a like view with the near mold side omitted.

45 The same reference characters denote the same parts throughout all the figures.

The liquid metal pot, pump and heating device are not shown in the drawings as these parts are well known in connection

with type casting machines and would here 55 take up unnecessary space.

The frame 1 and stationary bed 2 of the machine are of any suitable form and size and the bed 2 carries in a longitudinal recess a traveling mold carrier 3 with attached 60 mold sides 9 which latter pass between a stationary upper mold-part 4 and an under-mold 5, the latter being water-jacketed at 6 so as to receive circulation of a cold water current for cooling the freshly cast type. 65 Refrigeration is also provided, by means of the tubes 7* and jacket 22, for the removable headstock 7 which is well known and forms no actual part of this invention but helps to identify the type of casting machine 70 referred to and indicates the position of the induction nozzle 8 for the molten type metal. The upper mold part 4 is attached to the underside of the head-stock, or to a part connected with the latter as will be explained. 75

The under mold part 5 consists of a stationary plate of hard steel formed with sides 5* tightly fitted in the box or water jacket 6. The length of the stationary under-mold part 5 and box 6 is about equal to 80 the length taken in each direction by the traveling set of mold parts and intervening matrices. The width of the under-mold part 5 is slightly more than usual type-height. The mold sides 9 are made of steel 85 and extend beyond the under-mold part 5 by the width of the carrier 3 to which they are adjustably fixed by screws 11 and shaped nuts 12, which latter are lodged in grooves 13 of the carrier 3. The carrier 3 has at its 90 underside a rack 14 which is moved through the intervention of gear 15 actuated either by the handwheel 15* or by power as is usual in other type-casting machines. Between the suitable spaced fixed mold-sides 9 are 95 placed slidable matrices 16 each fitted with a screw stud 17 for adjusting the matrices in relation to their engagement with cams 19 and 23.

The lower portion of each matrix 16 is of 100 type width or thickness and fits the thin end portion 9* of the mold sides 9, while the upper portion of the matrix is wider so as to allow the drilling for the stud 17 without being weakened. The length of a matrix is 105 such as to provide a space equal to type-height when the matrix is slid inward. For imparting sliding motion to matrices, the

upper portion of each matrix is shouldered as shown so as to move with the forward shoulders 16* and the rear stud 17 between the front and rear cam surfaces 18 and 19 5 connected with a stationary cover plate 20 fixed to the bed 2 of the machine by screws 21. The cams 18 and 19 cause the matrices to slide between the mold sides 9 crosswise of the machine while traveling with the mold 10 carrier 3 longitudinally of the bed of the machine. A plate 20 with identical cams 18 and 19 is fixed toward each end of the machine at a suitable distance from the middle and between these two plates the headstock 7 15 is fixed. In front of the headstock is fixed a hollow water-cooled jacket 22 to the underside of which is fixed the aforementioned plate 4 which fits accurately over the front portion 9* of the mold sides 9 and so closes 20 same at the middle portion of the machine to receive the metal squirted in from the induction nozzle 8 separately into each recess between the mold parts as they pass along the bed of the machine. When a mold side 9 25 is in front of the nozzle 8, the corresponding matrix is positioned inward and its rear shoulder touches against a gradually curved central cam 23 which accurately sets the matrix to the required height of type the 30 adjusting stud 17 of the matrix being at this period not in action. The upper mold part 4 has a bead 22* to form a groove.

After the type has been cast, cooled and nicked during a portion of its travel in the 35 longitudinal direction of the machine, it arrives at an open slot 2* of the bed 2 beneath the cam 18, so that it can be gradually ejected from the mold by the matrix which is now pushed in this direction by the twin cams 18 and 19 fast in the plate 20. At the moment 40 when the type is fully projected from the slot it is taken up by a traveling belt 25 and carried with other type to a receptacle in the usual manner. After the last type from the 45 previous casting operation has been ejected, the movement of the machine is reversed and the carrier 3 takes the molds in the direction toward the opposite end of the machine so as to repeat the entire cycle of operations, 50 the parts at this side of the machine being the exact counterparts to those previously described.

I claim:

1. A double-acting type casting machine 55 comprising in combination a straight stationary bed, a reciprocating carrier, mold-sides fixed to the carrier, stationary top and bottom mold parts, a slidable matrix for

each mold, means for reciprocating the carrier in endwise direction of the machine, and 60 means for moving the matrices crosswise of the machine, as described and shown.

2. In a double-acting type casting machine having a straight bed, the combination with a reciprocating carrier, of a toothed rack 65 and gear for moving same, mold-sides fixed to said carrier, stationary top and bottom mold parts, slidable matrices in said molds, and means for reciprocating the matrices during the reciprocation of the carrier. 70

3. In a double-acting type-casting machine having a straight bed, the combination with a reciprocating carrier, of mold-sides fixed to the carrier, stationary water-jacketed top and bottom mold parts, slidable matrices in the 75 molds, and means for reciprocating the matrices during the reciprocation of the carrier, as described.

4. In a double-acting type-casting machine having a straight bed, the combination with a reciprocating carrier, mold-sides fixed to the carrier, stationary top and bottom mold parts, and slidable matrices in the molds, of an adjustable screw stud in the heel of each 80 matrix, as and for the purpose stated. 85

5. In a double-acting type casting machine having a straight bed, the combination with a reciprocating carrier, and mold sides fixed to the carrier, mold parts carried by the bed of slidable and adjustable matrices mounted 90 in the mold parts, and twin cam plates for controlling said matrices, as and for the purpose stated. 95

6. A double-acting type casting machine comprising in combination a straight stationary bed, a central headstock, a reciprocating carrier, mold parts carried by the bed, mold sides fixed to the carrier, adjustable sliding matrices in said mold parts, a central cam for setting each matrix during the moment of casting, water jackets for cooling the molds, a cam plate fitted with twin cams at each side of said headstock, said cams acting to move said matrices, an induction nozzle connected with the latter, gear for reciprocating the carrier, means for nicking the type, means for delivering the type and means for carrying same to a receptacle as described. 100 105

Signed at London, England, this 20th 110 May, 1912.

JOSEPH FREDERICK NORMAN.
